CLAIM

The ornamental design for a LED mirror makeup case as shown and described.

DESCRIPTION

FIG. 1 is a front, left, and top perspective view of a LED mirror makeup case, showing my new design;

FIG. 2 is a front, right, and bottom perspective view thereof;

FIG. 3 is a front view thereof;

FIG. 4 is a rear view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a perspective view of the LED mirror makeup case where the led mirror makeup case is in a folded state; and, FIG. 10 is a front, left, and top perspective view showing the LED mirror makeup case a position of use.
